UNITED STATES PATENT OFFICE.

CHARLES DAVID BONSALL, OF PITTSBURGH, PENNSYLVANIA, ASSIGNOR TO P. H. MURPHY COMPANY, OF NEW KENSINGTON, PENNSYLVANIA, A CORPORATION OF PENNSYLVANIA.

CAR ROOF.

Application filed August 19, 1926. Serial No. 130,146.

This invention relates to car roofs of the all steel riveted-up type wherein metal roofing sheets extend from side to side of the car and have overlapped marginal portions that are riveted to the lateral sheet supporting flanges of channel-shaped carlines.

In order to repair a roof of the above type it is necessary to shear the rivets that secure a damaged sheet to adjacent sheets. 10 Since the sheets are riveted to each other, this shearing operation is obviously liable to result in damage to an otherwise sound sheet and thus necessitate its replacement also.

15 The principal object of the present invention is an improved roof construction of the above type that will permit the easy replacement of one sheet without disturbing the fastening members of any other sheet. 20 Other objects are to produce a strong and durable roof of simple construction which can be easily assembled and cheaply manufactured.

25 The invention consists principally in locating the overlapped marginal portions of the sheets over the channels of the carlines and securing the sheets to the carlines on opposite sides of their overlapped margins. The invention also consists in the parts and 30 in the arrangements and combinations of parts hereinafter described and claimed.

In the accompanying drawings, which 35 form part of this specification and wherein like symbols refer to like parts wherever they occur—

Fig. 1 is a plan view of a portion of a car roof embodying my invention;

Fig. 2 is a longitudinal section through 40 the roof at the ridge on the line 2—2 in Fig. 1;

Fig. 3 is a vertical cross-section through the roof at the eaves, the section being taken between carlines on the line 3—3 in Fig. 1; and

45 Fig. 4 is a vertical cross-section through the eaves portion of the car, the section being taken through one of the carlines on the line 4—4 in Fig. 1.

The present roof comprises Z-bar side plates 5 that are connected by carlines 6 of 50 substantially channel-shaped section with outwardly projecting lateral flanges 7 at the tops of their side walls which serve as supports for the side marginal portions of metal roof sheets 8. The Z-bar side plates 5 are

preferably arranged with their webs horizontal and with their inner flanges projecting upwardly. The carlines 6 are deepest at the ridge and gradually decrease in depth towards the eaves where they are provided with 60 depending end flanges 9 that overhang the upstanding inner flanges of said side plates and are riveted or otherwise rigidly secured to the outer faces thereof. As shown in the drawing, the webs or bottoms of the trough 65 or channel-shaped carlines slope downwardly on opposite sides of the ridge, and the end of said carlines are left open to provide for drainage and ventilation of the troughs or channels. 70

The roof sheets 8 extend from eaves of the car and are supported along their side margins on the lateral top flanges 7 of the carlines 6. Said roof sheets are provided with down-turned eaves flanges 10 75 that overlap the upstanding inner flanges of the side plates and the ends of the carlines and are rigidly secured thereto by rivets. The adjacent side marginal portions of the sheets are overlapped to form lap joints 11, 80 which are located above the channels or troughs of the carlines; and the portions of the sheets located on opposite sides of their lap margins are supported on and rigidly secured to the lateral top flanges 7 of the 85 channel-shaped carlines 6.

As shown in the drawing, the lapped marginal portions of the sheets are located directly above the channels of the carlines, and are offset outwardly as at 12, opposite 90 the ends of the channels therein to form downwardly opening drain openings at the ends of the carlines, where said carlines serve as troughs for carrying away any water that may enter the roof joints. 95

Running boards 13 extend longitudinally of the roof at the ridge and are supported on the lateral top flanges of Z-shaped running board saddles 14 whose lateral base flanges rest on the sheets above the lateral side flanges of the carlines and are rigidly secured in position by the rivets that secure the sheets to flanges. 100

As stated above, the joints between the roof sheets are located over the channels of 105 the carlines and said sheets are secured to said carlines by means of fastening members that are clear of said joints. The advantage of this arrangement is that it permits the easy removal and replacement of one sheet 115

without damaging or disturbing any other sheet or the securing rivets therefor. Another advantage of the above construction is that the sheets require fewer rows of rivet holes than the sheets of previous roof constructions of the same type.

The invention is not limited to the precise shapes and arrangements of parts shown and described.

10. What I claim is:

1. A car roof comprising side plates connected by carlines, and roof sheets supported on said carlines with their adjacent margins overlapped, the overlapped portions of said sheets being located above said carlines and said sheets being secured to said carlines on opposite sides of their lapped portions.

2. A car roof comprising side plates connected by carlines, and roof sheets extending from side to side of said car and supported on said carlines with their adjacent margins overlapped, said sheets being rigidly secured to said carlines on opposite sides of their overlapped margins.

3. A car roof comprising side plates connected by carlines, of substantially channel-shaped section, and roof sheets supported on said carlines with their adjacent margins overlapped, said overlapped portions of said sheets being located over the channel of said carlines and said sheets being secured to said carlines clear of their overlapped margins.

4. A car roof comprising side plates connected by carlines, said carlines being of

substantially channel-shaped section and having lateral flanges at the edges of the side walls, and roof sheets extending from side plate to side plate with their adjacent margins overlapped over the channels of 40 said carlines, said sheets being secured to the lateral flanges of said carlines on opposite sides of their lapped margins.

5. A car roof comprising side plates connected by carlines having drain channels extending longitudinally thereof, and roof sheets extending from side plate to side plate with their adjacent margins overlapped over the drain channels of said carlines, said sheets being secured to the car 50 lines by fastening members located on each side of their overlapped margins.

6. A car roof comprising side plates connected by carlines, said carlines being of substantially channel-shaped section and having lateral flanges at the edges of the side walls and roof sheets extending from side plate to side plate with their adjacent margins overlapped over the channels of 60 said carlines, said sheets being secured to the lateral flanges of said carlines on opposite sides of their lapped margins, said sheets being turned down over the side plates and having their overlapped margins offset outwardly opposite the ends of the carlines to 65 form downwardly opening drain openings at the ends of the carlines.

Signed at New Kensington, Pa., this 16th day of August, 1926.

CHARLES DAVID BONSALL.
